R. J. COOK.
DRAFT YOKE,
APPLICATION FILED SEPT. 10, 1917.

Patented May 3, 1921.

Witness: 12

Inventor:
Roy J. Cook
By Sheridan, Sheridan & Smith, Atlys.

UNITED STATES PATENT OFFICE.

ROY J. COOK, OF CHICAGO, ILLINOIS, ASSIGNOR TO GEORGE C. MURRAY, OF CHICAGO, ILLINOIS.

DRAFT-YOKE.

1,377,004.

Specification of Letters Patent.

Patented May 3, 1921.

Application filed September 10, 1917. Serial No. 190,628.

To all whom it may concern:

Be it known that I, Roy J. Cook, a citizen of the United States, residing at Chicago, in the county of Cook and State of Illinois, 5 have invented certain new and useful Improvements in Draft-Yokes, of which the following is a specification.

This invention relates to improvements in draft yokes, and has for its object to provide a new and improved construction along the line of that shown in my previous Patent, No. 1,224,278, patented May 1, 1917. The main object of this invention is to provide a yoke which may be readily cast of 15 steel or iron, or the like, and in which a coupler butt may be readily inserted and retained in place, the construction being such as to permit ready assembling and disassembling, as desired.

20 In the structure of my patent mentioned above, I utilize two removable filler blocks coacting with inturned ends of the draft yoke and a shouldered coupler butt to transmit draft strains to the draft rigging. In 25 my present invention I am able to eliminate one of these filler blocks without sacrificing any of the advantages of my previous structure, and at the same time I make the structure more easy to assemble and cheaper to 30 manufacture.

These and other objects will be more fully set forth and described in the following specification and shown in the accompanying drawing, in which—

35 Figure 1 is a perspective view showing my improved yoke with one form of draft gearing mounted therein, a portion of the yoke and car structure being shown in section.

40 Fig. 2 is a transverse vertical section of the same.

Fig. 3 is a plan view of the yoke, a portion hereof being broken away, taken along the line 3 of Fig. 4; and

45 Fig. 4 is a side elevation of the yoke, showing the coupler butt and filler block in position prior to movement to final operative position.

Like numerals refer to like elements 50 throughout the drawings, in which 10 indicates generally a drawbar having a shouldered coupler butt 10^a. 11 designates my improved yoke, comprising top and bottom arms 11^a and 11^b, respectively, the same 55 being united at their rear ends by the por-

tion 11^c. The forward end is provided with integral side portions 11^d extending across between the arms 11^a and 11^b. The latter are formed with inwardly extending shoulders 11^e, 11^f at top and bottom, respectively, 60 such shoulders being spaced apart a sufficient distance to permit ready insertion therebetween of the coupler butt 10^a. On the under side of the arm 11^a of the yoke are the integral ribs 11^g, projecting inwardly from said arm and provided with horizontal under bearing surfaces 11^h, upon which may slide one face of the coupler butt 10^a.

A filler block 12 is provided, the same 70 having a shouldered portion 12^a at its forward end, and a bearing surface 12^b extending rearwardly therefrom, upon which rests the lower face of the coupler butt 10^a, the shoulder thereof coacting with the shouldered portion 12^a of the filler block. The latter is free to slide upon the lower arm 11^b, as is obvious, and when in assembled position, as shown in Fig. 1, this filler block 12 will bear against the shouldered portion 11^f 80 of the yoke arm 11^b and transmit thereto, as well as to the shoulder 11^e, the draft strains of the draw-bar and coupler mechanism. To provide an increased bearing surface for the filler block under such draft 85 strains, to decrease the possibility of shearing of the filler block, I provide integral lugs 11ⁱ on the inner faces of the side portions 11^d at the forward end of the yoke, the same extending upwardly from the 90 lower yoke arm shoulder 11^e to a point substantially at the top of the filler block shoulder 12^a—as shown in dotted lines in Fig. 4. These lugs 11ⁱ provide bearing surfaces at the sides of the shouldered filler 95 block 12 under draft strains and, together with the shoulder 11^f of the lower yoke arm, receive the draft stress of the draw-bar from the filler block 12. The ribs 11^g, at the same time, provide an upper bearing 100 surface for the coupler 10^a to maintain the same in the proper position to prevent its upper displacement under strain.

It will be obvious that my invention is susceptible of modifications and improvements, and I do not wish to be restricted to the form shown, except as defined in the appended claims.

What I claim is:

1. In combination, a yoke having upper 110

- and lower arms and a hooded forward end, transverse shoulders at the forward ends of said upper and lower arms, a coupler having a shouldered butt adapted to be inserted 5 between said shoulders into said forward end, and an integral shouldered block supported directly on said lower arm and engaging directly the lower shoulder of said butt, said block being insertible into said 10 hooded end from the rear thereof, after rearward displacement of said coupler, the upper surface of said butt engaging directly the upper arm of said yoke within said hooded end.
- 15 2. In combination, a yoke having its ends provided with inturned shoulders, a coupler having a shouldered butt constructed and arranged to readily be inserted between said shoulders, said yoke being further provided 20 with side portions extending between and serving to tie the front ends of said yoke arms, and a removable filler block coacting with one of said shoulders and being itself shouldered to coact with a shouldered coupler butt to prevent removal of the same when in assembled position and to transmit 25 draft strains therefrom to said yoke arm shoulder, said shouldered coupler butt being in direct contact with the other of said yoke 30 arm shoulders under draft stresses, said yoke arm being further provided with means presenting a bearing surface for said coupler butt and spacing said coupler butt from said last-named shouldered yoke arm, said 35 last-named means being constructed and arranged to prevent vertical displacement of said coupler butt.
3. In combination, a yoke having upper and lower arms provided with transverse 40 shoulders at their forward ends and comprising integral side walls uniting the forward ends of said arms, a draw-bar having a shouldered butt adapted to be inserted between said shoulders into the hooded end of 45 said yoke, the vertical dimension of said shouldered butt being less than the vertical distance between said upper and lower arms of said yoke, and an integral shouldered

filler block adapted to coact with one shoulder of said draw-bar butt and to engage directly with one of said shoulders of said yoke, said filler block being insertible into the hooded end of said yoke from the rear thereof and being adapted to space said butt from one arm of said yoke, the other 55 arm of said yoke comprising means adapted to coact directly with the wall of said butt opposite said filler block.

4. In combination, a yoke having upper and lower arms provided with transverse 60 shoulders at their forward ends and comprising integral side walls uniting the forward ends of said arms, a draw-bar having a shouldered butt adapted to be inserted between said shoulders into the hooded end of said yoke, the vertical dimension of said shouldered butt being less than the vertical distance between said upper and lower arms of said yoke, and a shouldered filler block 65 adapted to coact with one shoulder of said draw-bar butt and to engage directly with one of said shoulders of said yoke, said filler block being insertible into the hooded end of said yoke from the rear thereof and being adapted to space said butt from one arm of 70 said yoke, the other arm of said yoke being provided with an integral part adapted to coact with said butt and space the same from said other arm.

5. In combination, a yoke having upper 80 and lower arms and a hooded forward end, transverse shoulders at the forward ends of said upper and lower arms, a coupler having a shouldered butt adapted to be inserted between said shoulders into said forward end, 85 and an integral block supported directly on said lower arm and engaging directly the lower shoulder of said butt, said block being insertible into said hooded end from the rear thereof, after rearward displacement 90 of said coupler, the upper surface of said butt engaging directly the upper arm of said yoke within said hooded end.

In testimony whereof, I have subscribed my name.

ROY J. COOK.
